(57) CLAIM

The ornamental design for a handheld tool for opening a protective case, as shown and described.

DESCRIPTION

FIG. 1 is a front isometric view of a handheld tool for opening a protective case showing our new design;

FIG. 2 is a rear isometric view thereof;

FIG. 3 is a front view thereof;

FIG. 4 is a rear view thereof;

FIG. 5 is a right view thereof;

FIG. 6 is a top view thereof; and,

FIG. 7 is a bottom view thereof.

The broken lines depict unclaimed environment. The broken lines form no part of the claimed design.
